UNITED STATES PATENT OFFICE.

EDWARD W. BOWEN, OF CLEVELAND, OHIO, ASSIGNOR TO THE HYDRAULIC PRESSED STEEL COMPANY, OF CLEVELAND, OHIO, A CORPORATION OF OHIO.

SHORING FOR CONCRETE FORMS.

Application filed March 1, 1920. Serial No. 362,532.

To all whom it may concern:

Be it known that I, EDWARD W. BOWEN, a citizen of the United States, residing at Cleveland, in the county of Cuyahoga and State of Ohio, have invented a certain new and useful Improvement in Shoring for Concrete Forms, of which the following is a full, clear, and exact description, reference being had to the accompanying drawings.

10 This invention relates generally to concrete forms and more particularly to the improved means for and method of shoring or supporting the same.

The object of the invention is to provide a simple and efficient construction of shoring which will properly maintain in the forms in position while the concrete is being poured, and in which said forms can be quickly and easily removed when desired, 20 which is usually twenty-four hours after pouring.

Another object is to provide a shoring construction in which all of the wooden supports with the exception of the main upright 25 can be removed seven days after pouring; and a still further object is to provide a shoring construction in which the parts are detachably connected together by certain novel devices which can be used over and 30 over again and which will avoid nailing said parts together, certain of said devices being permanently connected to shoring members thereby eliminating loss by misplacement and also providing a material reduction of 35 time required in setting up the shoring as a whole.

With these, and certain other objects in view, the invention consists in the novel features of construction and in the manner of arranging the same, all of which will 40 be fully described hereinafter and set forth in the appended claims.

In the drawings forming a part of this specification, Fig. 1 is a sectional elevation 45 of a structure employing one form of my improved shoring; Fig. 2 is a sectional plan on the line 2—2 of Fig. 1; Fig. 3 is a detail view of the stringer supporting bracket; Fig. 4 is a detail view of the joist support 50 and spacer; Fig. 5 is a detail view of the pan supporting means.

In setting up a shoring in accordance with my invention, I employ a plurality of main upright supports A which are preferably 4 x 4 and any length desired according

to the height between floors. These uprights are preferably spaced equidistantly apart both longitudinally and transversely.

Each upright A has clevises B B attached to the opposite sides thereof near the upper end, each clevis comprising upper and lower bands B' which partially embrace the upright (as shown) and the outwardly bowed connecting portion B² and connected to each clevis B is a stringer supporting bracket C 60 comprising a base portion C' having an opening C² which fits over the outwardly bowed portion B² and a wedge D is passed through the bow B² and in front of the base portion C' and connects the bracket to 70 the clevis. The upper portion of the bracket is angled outwardly at C³ to receive the stringer E and the upper end of the bracket is bifurcated at C⁴ to receive the joist F which abuts at its end against the face of the 75 upright as most clearly shown in Fig. 2. In this way the uprights are braced and spaced at the same time.

Each stringer E has a plurality of stirrups G arranged thereon, each stirrup having a 80 saddle portion and the bowed leg portion G² and in connection with each stirrup I employ a joist support and spacer H having an opening H' in its lower portion into which fits the bowed leg G², and a wedge I 85 detachably connects the joist support to the stirrup. The upper portion of each joist support is bifurcated as shown at H³ to receive the joist K and in practice I prefer to permanently connect the stirrups to the 90 stringers at definite intervals so that the joist will be properly spaced apart, the proper distance.

Each joist has a plurality of stirrups L fastened thereon at definite points, each stirrup being bowed at L², and in conjunction with each stirrup I employ a pair of pan supporting arms M each slotted at M² and bowed at M² and having the positioning fingers M³ and M⁴ and a wedge N detachably connects each arm to its respective stirrup. The pans O rest upon the fingers M³ and M⁴ of the arms M and spacing strips P are interposed between the adjacent sides of each pair of pans said strips resting upon 105 the joists as shown.

Each upright supports two stringers, and each stringer supports and spaces a plurality of joists, and certain of the joists as before stated serve to center the uprights, and 110

the upright stringers, and joists, connected and arranged as herein shown and described provide a strong and durable shoring, and one which can be quickly and accurately placed, and by having the stirrup and clevises permanently connected all nailing at times of erection is avoided.

By having the various parts detachably connected, the different timbers can be quickly and easily removed and also the pans when desired.

In operation the first story shoring is set up, the pans arranged thereon and the concrete poured. At the expiration of twenty four hours the pans can be moved by moving the wedges N and detaching the supporting arm M. The shoring of the second story can then be set up, the uprights being arranged one directly above the other, and the stringers and joists connected thereto, ready to receive the pans for the second story and at the expiration of seven days the stringer and joists can be removed leaving the uprights standing and braced in any suitable manner and these uprights can remain until the floors have thoroughly settled and hardened.

It will of course be understood that all floors are reinforced by metallic reinforcements, and that pillars or columns are also constructed at the same time the floor is poured out and that each pillar or column is

reinforced and bonded with the floor reinforcements, but for clearness of illustration of the shoring these reinforcements have been omitted from the drawings.

I do not make any claim to the detailed construction of the clevis stirrup and detachable bracket.

Having thus described my invention, what I claim is:

1. A shoring comprising a plurality of uprights having brackets detachably connected thereto, stringers supported upon said brackets, joists arranged upon said stringers and abutting said uprights, said brackets having a portion adapted to embrace and position said joists, and means detachably connected to said joists for supporting a plurality of pans. 50

2. A shoring comprising a plurality of uprights having clevises connected thereto, brackets detachably connected to said clevises, stringers supported by said brackets, joists arranged upon said stringers, said brackets having a portion adapted to embrace and position said joists, stirrups connected to said joists, and arms detachably connected to said stirrups for supporting a plurality of pans. 60

In testimony whereof, I hereunto affix my signature.

EDWARD W. BOWEN.
